US00D686729S

(12) **United States Design Patent**
Christensen et al.(10) **Patent No.:** US D686,729 S
(45) **Date of Patent:** ** Jul. 23, 2013(54) **OPHTHALMIC STRUCTURE**(71) Applicant: **OASIS Medical, Inc.**, Glendora, CA (US)(72) Inventors: **James Marlow Christensen**, Glendora, CA (US); **D. Michael Colvard**, Encino, CA (US)(73) Assignee: **Oasis Medical, Inc.**, Glendora, CA (US)(***) Term: **14 Years**(21) Appl. No.: **29/433,064**(22) Filed: **Sep. 25, 2012****Related U.S. Application Data**

(63) Continuation of application No. 13/275,685, filed on Oct. 18, 2011, now Pat. No. 8,439,833.

(51) **LOC (9) Cl.** ..... **24-02**(52) **U.S. Cl.**USPC ..... **D24/150**(58) **Field of Classification Search**
